[57] CLAIM

The ornamental design for a vehicle splash guard, as shown and described.

DESCRIPTION

FIG. 1 is a front perspective view of a vehicle splash guard showing my new design, it being understood that the broken lines are for illustrative purposes only and form no part of the claimed design;
FIG. 2 is an enlarged top plan view thereof;
FIG. 3 is an enlarged left side elevational view thereof;
FIG. 4 is an enlarged front elevation view thereof;
FIG. 5 is an enlarged right side elevation view thereof;
FIG. 6 is an enlarged rear elevation view thereof; and
FIG. 7 is an enlarged bottom plan view thereof.

FIG. 2

FIG. 3

FIG. 4

FIG. 5
